TIME CONTROL LOCK

George F. Claus, Pasadena, Calif.

Application April 3, 1941, Serial No. 386,709

3 Claims. (Cl. 70—267)

This invention relates generally to locking devices for closures and pertains particularly to a time actuated or controlled lock for doors.

The primary object of the present invention is to provide a novel and improved mechanism for controlling a locking apparatus for a door structure in such way that such apparatus cannot be manipulated for the opening of the door until after the passage of a predetermined period of time. Such mechanism may be used upon doors of private houses, institutions or safes and when set, is designed to positively prevent the releasing of the door locking apparatus until after a certain period of time has elapsed.

Another object of the invention is to provide a control mechanism for a door securing apparatus which may be coupled with a clock mechanism either of the electrical type or of a spring controlled type or may be operated by a slow speed electric motor, the apparatus including a feed screw and nut thereon, which is slowly fed to a position where it will release the door locking apparatus.

The invention will be best understood from a consideration of the following detailed description taken in connection with the accompanying drawing, it being understood, however, that the invention is not to be considered as limited by the specific illustration or description but that such illustration and description constitutes a preferred embodiment of the invention.

In the drawing:

Fig. 1 illustrates a door structure partly in elevation and partly in section, showing the time controlled apparatus embodying the present invention operatively coupled therewith.

Fig. 2 is a horizontal section taken on the line 2—2 of Fig. 1.

Fig. 3 is a vertical section taken on the line 3—3 of Fig. 1.

cessed, as indicated at 6, and within one recess is a stud 7 while the opposite recess has a similar stud 8 disposed therein, the latter stud carrying a portion of the locking apparatus, as will be hereinafter more fully described.

The door structure 3 is supported, as is set forth in my prior patent referred to, to be swung on any one of four axes, each axis being located at a corner of the door. The suspension means by which the door may be swung in this manner comprises a pair of vertically spaced hinge units 9 located at each of the four corners of the door, two of these hinge units being coupled with the stud 7 while the other two are coupled with the stud 8. These hinge units are in the usual two sections which are pivotally joined together by pintles 10 and each pair of pintles is operatively coupled with a vertically reciprocable rod 11 which makes it possible to remove the pintles of any three pairs of hinges, so that the fourth pair may function to support the door for opening movement. These pintle rods are controlled by the horizontally disposed levers 12 which extend across the adjacent edge of the door between the same and the jamb to the far side of the wall structure in which the door is mounted, so that the pintles can be shifted as desired, from either side of the door. After the selected hinges have been uncoupled by the shifting of their pintles and, of course, after the door locking apparatus has been released, the door can be shifted toward the jamb adjacent which is located the pair of hinges selected for the support of the door so as to separate the parts of the remote pairs of hinges and thus permit the door to be swung freely to opened or closed position. This shifting movement of the door in the frame is accomplished by the swivel screw 13 supported by each jamb and having threaded connection with the adjacent stud.

The locking apparatus for the door comprises cooperating parts carried by the door and a jamb. In the door there is mounted an interiorly threaded sleeve 14 which opens through the adjacent vertical edge of the door body and which at its inner end abuts against a guide 15 in which is threaded a pin 16, one end of which is accessible from within the cabinet or chamber 4. In the stud 8 which opposes the threaded sleeve 14, there is mounted a threaded sleeve 17 through which is threadably extended the exteriorly threaded bolt guide cylinder 18, which has upon that end remote from the door, a head 19 by which its rotation in the sleeve 17 is effected. This bolt guide cylinder is designed to be threaded inwardly to abut against the outer end of the sleeve 14.

At the side of the door structure upon which the jamb 8 is located, the wall in which the door is mounted is provided with a chamber 20 either

in the structure illustrated, the numeral 1 generally designates a door frame having the opposite side uprights or jambs 2. Within the frame is disposed the door structure 3 which has a central cabinet or chamber 4 which is closed by the opposite doors or panels 5.

The jambs 2 have their opposing faces re-

or both sides of which may be reached through lock controlled doors 21. The head 19 of the cylinder 18 is accessible from within this chamber 20. This chamber houses the time controlled mechanism hereinafter described.

The numeral 22 designates the door securing bolt and, as shown, this bolt passes through the threaded cylinder 18 and has one end extended into the wall chamber 20, while upon its other end is a threaded head 23 which has threaded engagement within the door carried sleeve 14. The end of this head 23 is provided with a longitudinally directed threaded bore 24, in which is engaged the threaded locking pin 16. The head 23 of the bolt is of larger diameter than the body of the bolt and, therefore, cannot be drawn into the guide cylinder 18, consequently, it will be seen that when the head of the bolt is threaded into the door carried sleeve 14 and the guide cylinder 18 is threaded inwardly until it is in contact with the sleeve 14, the bolt cannot be retracted until the cylinder is first retracted.

Within the chamber 20 is mounted the operating unit for the time controlled mechanism, which unit is indicated generally by the numeral 25. This unit may constitute an ordinary spring operated clock mechanism, an electric clock or an electric motor. From the operating unit extends a shaft 26 which has one end supported in a suitable bearing, as indicated at 27, and a portion of this shaft is screw threaded, as indicated at 28. Supported upon the threaded portion 28 of the shaft 26 is a nut 29 which has a radial extension 30. The threaded shaft 26 is parallel with and directly below the bolt 22, and there is secured to and supported upon the end of the bolt 22, a hood body 31, the lower or under side of which has the axially extending recess or slot 32, in which the portion 30 of the nut slidably engages. Extending upon opposite sides of the nut 29 and parallel with the shaft 26 are guide arms 33 which prevent the nut from turning with the shaft but cause it to move longitudinally as the shaft is rotated.

The shaft 26 carries a collar 34 provided with a number of apertures to receive a suitable pin, not shown, by which rotation of the shaft may be effected by hand. This is provided for the resetting of the mechanism as will hereinafter be described.

The threads on the shaft may be of any desired pitch so as to cause the nut to be advanced toward the adjacent door jamb at a rapid or slow pace, according to the length of time which it is desired shall elapse between the time when the door is locked and the time when it is to be released for opening. Provision may also be made for the removal of the shaft, so that shafts having threads of different pitch may be substituted when the time period is to be changed, this arrangement being particularly desirable where the shaft is to be turned by a motor.

From the foregoing, it will be readily seen that when the door has been secured by the provision of the bolt 22 into the door carried threaded sleeve 14 and the cylindrical guide 18 has been advanced inwardly against the sleeve 14 in the manner shown, the shaft 26 can be rotated to bring the extended portion of the nut 29 into the slot of the hood 31, this setting of the nut with respect to the hood being manually accomplished. After the mechanism has thus been set, the op-

erating unit may be started so that the nut will be caused to be fed by the screw 28 slowly toward the jamb so that it will release the hood 31 after the passage of a predetermined period of time. 5 If, for example, the pitch of the screw is coordinated with the speed of rotation of the time unit 25, so that when the nut is fully within the hood, it will take a period of sixteen hours to be advanced to a position where it will be fully released from the hood, it will be seen that if the 10 clock is used in a business establishment which closes at five o'clock and the time clock is set into operation at this time, the bolt 22 will not be released by the nut 29 until nine o'clock the following morning, which may be the opening time for the establishment. After the hood has thus been released by the nut, it will be readily seen that the other elements of the locking apparatus can be manipulated to release the door, by first backing out the guide 18 away from the door carried sleeve 14, then releasing the threaded pin 16 from the headed end of the bolt, and then rotating the bolt to back it out of the sleeve 14.

What is claimed is:

1. A time control locking mechanism comprising a bolt supported to have combined rotary and longitudinal movement, and mechanism for maintaining the bolt against rotary movement for a predetermined period comprising a worm, 25 a nut carried by the worm, means facilitating the establishment of a sliding connection between the nut and said bolt, said worm when rotated for a predetermined period effecting relative movement of the nut and the bolt to disengage the same one from the other, and means connected with the worm for imparting rotary motion thereto.

2. A time control locking mechanism comprising, a bolt supported to have combined rotary and longitudinal movement in shifting between locking and unlocking positions, and mechanism for maintaining said bolt against rotary movement for a predetermined period after it has been shifted to locking position, comprising a body 40 carried by the bolt and having a groove extending lengthwise of the bolt, a worm supported for rotation coaxially with the bolt, a nut threadably connected with the worm and adapted for sliding engagement in said groove, and a prime mover operatively coupled with the worm to effect rotation of the same.

3. A time control locking mechanism comprising, a bolt supported to have combined rotary and longitudinal movement in shifting between locking and unlocking positions, and mechanism for maintaining said bolt against rotary movement for a predetermined period after it has been shifted to locking position, comprising a body carried by the bolt and having a groove extending lengthwise of the bolt, a worm supported for rotation coaxially with the bolt, a nut threadably connected with the worm and adapted for sliding engagement in said groove, and a prime mover operatively coupled with the worm to effect rotation of the same, said worm having threads of a predetermined pitch and said groove having such length in relation to the pitch of the threads as to effect movement of the nut from a position in full engagement in said groove 55 to a position free of the groove within a predetermined period of time.

GEORGE F. CLAUS.
